US00D915507S

(12) **United States Design Patent** (10) **Patent No.:** **US D915,507 S**
(45) **Date of Patent:** **** Apr. 6, 2021**

(54) **PAPER CUTTER**

(71) Applicant: **MAKE GREAT SALES LIMITED**,
Wanchai (HK)

(72) Inventors: **Bruce Peter Cran**, Ho Chi Minh (VN);
Kin Choi Lee, Wanchai (HK)

(73) Assignee: **Make Great Sales Limited**, Hong
Kong (HK)

(**) Term: **15 Years**

(21) Appl. No.: **29/713,351**

(22) Filed: **Nov. 15, 2019**

(51) **LOC (13) Cl.** **18-04**

(57) **CLAIM**

The ornamental design for a paper cutter, as shown and
described.

DESCRIPTION

FIG. 1 is a top perspective view of a paper cutter, in
accordance with our design;

FIG. 2 is a bottom perspective view of the paper cutter of
FIG. 1;

FIG. 3 is another top perspective view of the paper cutter of
FIG. 1;

FIG. 4 is a front view of the paper cutter of FIG. 1;

FIG. 5 is a rear view of the paper cutter of FIG. 1;

FIG. 6 is a left-side view of the paper cutter of FIG. 1;

FIG. 7 is a right-side view of the paper cutter of FIG. 1;

FIG. 8 is a bottom view of the paper cutter of FIG. 1; and,

FIG. 9 is top view of the paper cutter of FIG. 1.
